UNITED STATES PATENT OFFICE.

PATRICK K. O'LALLY, OF BOSTON, MASSACHUSETTS.

SHUTTER-WORKER.

SPECIFICATION forming part of Letters Patent No. 231,677, dated August 31, 1880.

Application filed January 17, 1880.

To all whom it may concern:

Be it known that I, PATRICK K. O'LALLY, of Boston, in the county of Suffolk and State of Massachusetts, have invented certain Improvements in Means for Operating and Fastening Blinds and Shutters, (Case B,) of which the following is a specification.

This invention has for its object to provide improved means for operating an outside blind or shutter and fastening the same in any desired position from the inside of the window.

To this end my invention consists in the improved means which I will now proceed to describe and claim.

15 Of the accompanying drawings, forming a part of this specification, Figure 1 represents a horizontal section of a portion of a window casing and blind. Fig. 2 represents a section on line $x-x$, Fig. 1. Figs. 3 and 4 represent enlarged sections on line $y-y$, Fig. 1, showing the bolt in different positions. Fig. 5 represents a section of one of the parts detached, and Fig. 6 represents a front view of another part detached.

25 Similar letters of reference indicate like parts in all the figures.

In the drawings, A represents a window-casing, and B represents an ordinary blind hinged to the casing in the usual manner. One of 30 the hinges C of the blind is provided with a pinion, D, which is rigidly attached to the portion of the hinge that is attached to the blind.

E represents a rack formed on a rod, E', which is suitably secured to a bolt, F, in such 35 manner that said bolt can be rotated without disturbing its connection with the rod E'.

G represents a socket or bushing secured to the casing. Said socket has a screw-threaded orifice adapted to receive the bolt F, and the 40 screw-threads are cut away to form channels or enlargements $g-g$, extending through the socket and having two threaded portions, $g'-g'$.

The bolt F is screw-threaded on its periphery, and the threaded portion is partially cut away at $f-f$, lengthwise of the bolt, which cut-away portions are separated by threaded portions $f'-f'$, the cut-away portions being of such width that they will receive the screw-threaded portions $g'-g'$ of the socket and permit the threaded portions $f'-f'$ to fit in the

cut-away enlargements $g-g$ of the socket, as shown in Fig. 3. When the bolt is in this position it is adapted to be moved freely through the socket and cause the rack E to turn the blind on its hinges.

When the bolt is partially turned from the position shown in Fig. 3 its threaded portions f' engage with the threaded portions g' of the socket, as shown in Fig. 4, so that the bolt is locked and prevented from moving lengthwise.

It will be seen that the blind can be fastened by the described means in any desired position, whether open or shut, and as said bolt is accessible only from the inside of the window, it follows that the blind cannot be moved from the outside without breaking the hinge or the window.

The rod E' is preferably threaded on its inner end and screwed into a tapped socket in the bolt, the threads of the rod and socket 70 having a quicker pitch than the threads of the bolt F and socket G, so that in case the blind is either opened or closed, so that the bolt cannot be moved lengthwise in one direction or the other, and the bolt F is in such position 75 that its threads do not register with the threads of the socket, the bolt may be moved sufficiently to enable its threads to register with the threads of the socket by slightly rotating the bolt, such rotation causing the 80 threads of the rod E' and its socket to give the bolt F a slight longitudinal movement sufficient to accomplish the desired result.

I prefer to provide the hinge with a lug, l, to bear against the rack and prevent the latter from being separated from the pinion either by being pressed up, downward, or outward, as shown in Figs. 1 and 2.

I claim as my invention—

1. As a means for operating and fastening 90 a blind or shutter, a socket or bushing adapted to be secured to a window-casing and provided with internal screw-threads which are partially cut away to form longitudinal channels or enlargements in the socket, a bolt provided 95 with screw-threads formed to engage the threads of the socket and partially cut away to correspond with the socket, as described, and a rod secured to the end of the bolt and provided with rack-teeth adapted to mesh with 100

pinions or segments rigidly attached to the blind or shutter, as set forth.

2. The combination of the partially-threaded rotary bolt F, its partially-threaded socket G, 5 the rod E', having the rack E, and the pinion D, engaging the rack and preventing the longitudinal movement of the rod when the blind is opened or closed, the rod having a threaded end and the bolt having a threaded socket to 10 engage the threaded end of the rod, whereby the bolt is caused to move longitudinally when

rotated, substantially as and for the purpose specified.

In testimony whereof I have signed my name to this specification, in the presence of two 15 subscribing witnesses, this 13th day of January, 1880.

PATRICK K. O'LALLY.
